(57) **CLAIM**

The ornamental design for a mating connector, as shown and described.

DESCRIPTION

FIG. 1 is a top plan view of my new and ornamental design for a mating connector;

FIG. 2 is a side elevation view thereof;

FIG. 3 is an end view thereof;

FIG. 4 is a perspective view thereof from above; and,

FIG. 5 is a cross-sectional view taken along section line 5—5 of FIG. 2 and illustrating the counter-sunk hole formed in the mating connector.
